UNITED STATES PATENT OFFICE

147,348

DESIGN FOR A RESISTANCE WELDING
MACHINE

Joseph J. Panik, Detroit, Mich., assignor to Banner Products Company, Milwaukee, Wis., a corporation of Wisconsin

Application February 6, 1946, Serial No. 126,331

Term of patent 7 years

(Cl. D26—5)

To all whom it may concern:

Be it known that I, Joseph J. Panik, a citizen of the United States, residing at Detroit, in the county of Wayne and State of Michigan, have invented a new, original, and ornamental Design for a Resistance Welding Machine, of which the following is a specification, reference being had to the accompanying drawing, forming part hereof.

In the drawing:

Fig. 1 is a side elevational view of a resistance welding machine, showing my new design;

Fig. 2 is a front elevational view thereof; and

Fig. 3 is a plan view of the machine.

I claim:

The ornamental design for a resistance welding machine, substantially as shown.

JOSEPH J. PANIK.
